UNITED STATES PATENT OFFICE.

HUBERT SEFFER, OF HOUSTON, TEXAS.

HOODWINK.

SPECIFICATION forming part of Letters Patent No. 589,307, dated August 31, 1897.

Application filed December 30, 1896. Serial No. 617,486. (No model.)

To all whom it may concern:

Be it known that I, HUBERT SEFFER, a citizen of the United States, residing at Houston, in the county of Harris and State of Texas, have invented a new and useful Hoodwink, of which the following is a specification.

This invention relates to hoodwinks or goggles; and the principal object of the invention is to provide a device of this character 10 in which the eyepieces or hoods are adjustable toward and away from each other, so that the positions thereof may be accommodated to the eyes of the wearers, whereby the same hoodwink may be used repeatedly upon 15 different persons and adjusted accurately to suit the width between the eyes and to render the eyepieces comfortable to the wearer.

The invention also has for its object to connect the eyepieces by means of an elastic 20 disposed in such manner that it will not press with any considerable force against the nose of the wearer and thereby detract from his comfort.

With the above objects in view the invention 25 consists in certain novel features and details of construction, as hereinafter fully described, illustrated in the drawings, and finally embodied in the claims.

In the accompanying drawings, Figure 1 is 30 a perspective view of the improved hoodwink or goggles. Fig. 2 is a horizontal sectional view of the same.

Similar numerals of reference designate corresponding parts in both figures of the drawings.

Referring to the accompanying drawings, 35 1 designates an elastic cord or web of a length sufficient to enable the same to be passed around the head of any person and the ends 40 tied in any convenient manner. Upon this elastic cord is arranged a pair of eyepieces 2. These eyepieces may be of any suitable material—such as metal, rubber, leather, felt, enameled glass, &c.—and are preferably 45 made perfectly opaque, although, if desired, the said eyepieces may be constructed of a material which is to any desired extent translucent. The eyepieces 2 are of an ellipsoidal form and are also made concavo-convex in 50 cross-section, the concaved surfaces of such pieces being disposed inward, so as to afford cavities or cups, which will surround the eye

balls and sockets and permit the eyes to be freely opened without any inconvenience whatever.

Each of the eyepieces 2 has arranged centrally thereof and attached rigidly to its outer surface an eye or loop 3, and a similar eye or loop is located at or near the outer corner or edge thereof. Through these eyes or loops is 60 passed the elastic cord 1, and as such cord naturally takes a straight line from the central eye of one eyepiece to the corresponding eye of the other eyepiece the space between the eyepieces and the elastic cord is left perfectly free for the nose of the wearer, so that no material pressure of the elastic cord against the nose is had.

By means of the construction above described, and as the elastic cord is rove loosely 70 through the eyes 3, the eyepieces may be slid together or apart upon said cord, so as to correspond exactly to the distance apart of the eyes of the particular person upon whom the hoodwink is to be placed. Where the eyepieces are constructed of opaque material and applied closely to the face of the wearer, every vestige of light will be excluded from the vision, while at the same time the eyes may be freely opened and closed, thereby rendering the device perfectly comfortable. The 75 device is particularly valuable during the progress of an electrical storm, as it will effectively exclude flashes of lightning from the vision and thereby obviate shocks, which are 80 so distressing to the nervous systems, especially of weak and delicate women. The device may also be used for other purposes, which will readily suggest themselves.

Changes in the form, proportion, and minor 85 details of construction may be resorted to without departing from the spirit or sacrificing any of the advantages of this invention.

Having thus described the invention, what is claimed as new is—

1. The combination with an elastic cord or web, of a pair of eyepieces mounted thereon and capable of adjustment longitudinally thereof, substantially as described.
2. The combination with a pair of eyepieces 100 provided with eyes or loops, of an elastic cord passing through said eyes or loops and adapting the eyepieces to be adjusted as to their distance apart, substantially as described.

100

3. A pair of eyepieces or hoods each having upon its outer surface a central eye, of an elastic cord passing through said eyes and adapting the said eyepieces to be moved toward or away from each other, substantially as described.

4. The combination with a pair of eyepieces having upon their outer surfaces the central eyes or loops, and similar eyes or loops at or near their outer edges, of a cord passing

through the several eyes or loops, substantially as and for the purpose described.

In testimony that I claim the foregoing as my own I have hereto affixed my signature in the presence of two witnesses.

HUBERT SEFFER.
